[57] CLAIM

The ornamental design for a resistor coolant container, as shown and described.

DESCRIPTION

FIG. 1 is a perspective view of a resistor coolant container showing my new design, it being understood that the broken lines are for illustrative purposes only;

FIG. 2 is an enlarged side elevation view thereof, the opposite side being a mirror image of that shown;

FIG. 3 is an enlarged end elevation view thereof;

FIG. 4 is an enlarged end elevation view thereof opposite to that shown in FIG. 3;

FIG. 5 is an enlarged top plan view thereof; and

FIG. 6 is an enlarged bottom plan view thereof.

FIG. 1

FIG. 3

FIG. 2

FIG. 4
